DRAINAGE SYSTEM

Filed May 4, 1928

UNITED STATES PATENT OFFICE

ED MURRAY, OF COLLEGE VIEW, NEBRASKA

DRAINAGE SYSTEM

Application filed May 4, 1928. Serial No. 275,089.

My invention relates to drain construction, and more particularly to means for draining a depressed area such as a lagoon, swamp or portion of land on which water stands for a period during each year, the principal object of the invention being to provide a maximum of drainage elements in a minimum of space for effectively draining a large area without interfering with the tilling of the area. Further objects of the invention are to provide permanently operative drainage means, and to trap soil particles and prevent outflow thereof with the drained water. A particular object of the invention is to equalize the air pressure between the atmosphere and a well receiving water from sunken drains.

In accomplishing these and other objects of the invention I have provided improved details of structure, the preferred forms of which are illustrated in the accompanying drawings, wherein:

Fig. 1 is a perspective view partly in section of a drainage construction embodying my invention.

Fig. 2 is a detail central vertical section of a portion of the construction including the well head and a well cover.

Fig. 3 is a detail perspective view of the upper end of the well casing, and portions of tiling connected thereto, and the cover separated from the casing and provided with a pressure equalizing tube shown fragmentarily.

Referring in detail to the drawings:

1 designates generally a depressed area such as a low portion of a field, and 2 the low point of the area. Receiving trenches are dug in spaced relation with the low point 2, and they are represented in the illustrative application of the invention as comprising a single circular trench 3, the low point being the center on which the trench circle is formed. All portions of the trench may be of equal depth. Radial ditches 4 are then dug from the trench to the center 2 of the area, the floors 5 of the ditches inclining downwardly from the floor 6 of the trench 3.

A well 7 is then provided at the center of the area, extending to porous strata 8, and a

casing 9 is installed in the well, to receive water conducted by the ditches to the center of the area. The upper edge 10 of the casing projects slightly above the mouth of the well.

Drainage tile 11 are laid on the floor of the circular trench, to comprise a ring-like conduit to intercept and receive water that may run toward the center of the depressed area and water that may fall adjacent the trench. Radial tile conduits 12 are installed in the ditches, the outer ends of the tile conduits 12 being connected into the circular conduit, and the inner ends extending in notches 13 of the casing for support from the casing, to receive water from the circular conduit and from the radial ditches and conduct it to the well.

The upper edge 10 of the casing is free, because of the projection above the floor of the ditches and the insetting of the radial tile in the notches. Resting on the edge 10 is a cover 14 comprising a disk-like member preferably of concrete, having a central aperture 15 to admit a tube 16, which is fixed in the cover, the lower end of the tube extending into the well and the upper end extending to a substantial distance above the surface of the surrounding land.

A porous filler 17, for example, gravel, is installed on the tile to fill the trench and ditches, for filtering soil and other solid particles from the water that passes through the channels to the tile.

Drainage apparatus of the character described may be provided at a selected position in relation to a depressed area, for example, at one edge thereof, for draining all or a portion of the area. The trench may be dug in circular form, the circle having a diameter appropriate to the contour of the land, for example 60 feet; the trench may have a depth of 18 inches, and width of 18 inches. The radial ditches have floors aligning with the floors of the trench at their outer ends, and incline downwardly toward the well, the ditches being, for example, 3 feet deep at their well ends. The concrete cover shields the mouth of the well, and when the porous material is deposited, the

air tube assures movement of air from the well, to prevent hindrance of flow of water into the well. The porous material retains the soil for the area by trapping the soil and checking the velocity of the water, and also 5 prevents clogging of the tile and well by solid particles.

What I claim and desire to secure by Letters Patent is:

- 10 1. In a drainage construction for draining a depressed area, a well at the low point of said area, trench portions circumferentially disposed to said well to intercept water flowing toward the well, and radial channels connecting the well with said trench portions for conducting water from the trench portions to the well.
- 20 2. In a drainage construction, a circular trench, a diametrical ditch connected with the circular trench and having a floor declining towards the center on which the circle is formed, and a well at said center for receiving water conducted from the circular trench by the diametrical ditch.
- 25 3. In a drainage construction for draining a depressed area, intersecting trenches adapted to contain a porous filler, a well at the intersection of the trenches, a cover for the well having a tube-receiving aperture, 30 and a tube extending into the well and above the upper edges of the trenches for equalizing air pressure between the atmosphere and the well.
- 35 4. Drainage apparatus comprising a well including a casing having notches in its upper edge, drainage tile disposed circumferentially to the well, conduits having inner ends seated in said casing notches connecting the tile with the well, a cover on the casing, a tube extending through the cover into the 40 casing, and a porous filler covering the cover, tile and conduits, the tube projecting above the filler to atmosphere.
- 45 5. In a drainage system of the character described for draining a depressed tillable area, a circular conduit comprising drainage tile adapted to intercept water flowing over the area, a well at the center on which the conduit is formed including a casing having its upper end located below the conduit and having notches in its upper edge, tile conduits connected with said circular conduit and having inner ends resting in the notches of said casing, a cover seated on the 50 upper end of the casing, a tube fixed in the cover and extending into the casing, and a porous filler covering said conduits for retaining soil to conserve the tillable character of the area.
- 55 6. In a draining system of the character described including a tile conduit and a well, a casing in said well having notches adapted to receive the inner end of the conduit and to leave the upper edge of the casing free, 60 a cover comprising a disk adapted to rest

on the upper edge of the casing, and a tube fixed in the cover having one end adapted to extend into the casing.

In testimony whereof I affix my signature.

ED MURREY.
